UNITED STATES PATENT OFFICE.

DAVID O. PAIGE, OF DETROIT, MICHIGAN.

CRANE-TONGS.

SPECIFICATION forming part of Letters Patent No. 425,452, dated April 15, 1890.

Application filed September 11, 1889. Serial No. 323,663. (No model.)

To all whom it may concern:

Be it known that I, DAVID O. PAIGE, a citizen of the United States, residing at Detroit, county of Wayne, State of Michigan, have 5 invented a certain new and useful Improvement in Crane-Tongs; and I declare the following to be a full, clear, and exact description of the invention, such as will enable others skilled in the art to which it pertains to make 10 and use the same, reference being had to the accompanying drawings, which form a part of this specification.

In the drawings, Figure 1 is a view in side elevation of an apparatus embodying my invention. Fig. 2 is an end elevation of the 15 same. Fig. 3 is a plan view of the lever or tongs.

It is the purpose of my invention to produce an apparatus for charging and discharging 20 articles or vessels into or from an oven.

In the instance illustrated in the drawings I have shown it adapted for handling large metallic cylindrical rings used in the construction of metallic beer-casks into and from 25 an enameling-oven, although it will be understood, of course, that for articles of other shapes the forms of the jaws may be altered to correspond thereto, and that, instead of being made to handle simply a single article, it 30 may be adapted to handle pots or vessels which are filled—as, for instance, the annealing pots in a malleable-iron works, &c.

In carrying out my invention, A represents an overhead track or railway of suitable construction. That shown is strong and convenient and consists of two rails a , sustained by truss-work of uprights a' and braces a'' . This is suitably supported from above. Depending from this is a crane B, sustained at the 40 top by, preferably, four wheels B' , two upon each rail a . At its lower end it is engaged by collars b to a trunnion-bar C' , to which the lever C of the tongs is fixed. These collars b are preferably provided with supporting-stems b' , which are made adjustable up and down by means of adjoining nuts b'' . This affords means for regulating the height of the 45 tongs or lever to any convenient level to conform to any work that is habitually handled. The tongs are constructed essentially as follows: To the shaft or lever C cross-arms

C^2 are fixed, and to the shaft and cross-arms the sliding jaws C^3 are engaged. These are connected by pitmen c to a central rotary disk c' , and this disk is engaged with a hand-lever C^4 by a rod c^3 , so that by forcing this hand-lever toward the jaws the latter are closed toward their common center upon the ring or other object that is being handled, and by forcing the hand-lever in the opposite 60 direction the jaws are expanded. At the other end of the shaft or lever C is the lifting-handle C^5 , and a counterpoise-weight C^6 is provided for use when desirable. In handling large rings or similar objects in enameling-ovens or other ovens it is important that the tongs shall deliver the object at a particular defined place, and it is equally important to grasp the article with accuracy and without disturbance when removing it from the 70 furnace. To accomplish this object I unite the tongs or lever rigidly to the depending crane, so as to have no lateral motion, as shown in the drawings, whereby they are caused to move accurately to the given position in charging and discharging. In other cases, however, where small pots or articles are to be charged into different parts of the furnace provision is made for so doing by 75 swiveling the tongs to the lower end of the 80 crane, as shown by the dotted lines, which will enable the tongs to be turned laterally about this point as a vertical pivot.

I would have it understood that where the object or pot to be handled is square or of 85 other shape the jaws may be correspondingly shaped to accommodate the same, and other details may be varied without departing from my invention.

To operate the device, the workmen seize 90 the handle C^5 and bring the jaws to the article to be lifted. Then by pulling the hand-lever the jaws are opened. They are then brought into position, embracing the object, and the jaws are closed upon it by the hand-lever. It is then lifted and run forward into or back out of the oven. The crane, of course, moves along the tracks a .

What I claim is—

1. The apparatus for charging and discharging 100 articles from an oven, the same consisting of the combination, with an overhead track,

- of a crane with a rigid arm projecting downward therefrom, tongs provided with a trunnion-shaft engaged with the crane, sliding jaws engaged by pitmen with a rotary disk, 5 and a connecting-rod and hand-lever for operating the jaws by rotating the disk, and a lifting-handle at the free end of the lever C, substantially as described.
2. The combination, with the tongs and the 10 overhead track, of a depending crane engaging one with the other, said crane consisting of a rigid frame supported at the top by four wheels adapted to travel along said track, substantially as described.
- 15 3. The combination, with the overhead track, the crane, and the tongs, of a horizontal trunnion-shaft at right angles to the shaft of the tongs, the latter engaged rigidly with said trunnion-shaft, whereby the tongs may 20 be moved up and down about the horizontal

trunnion, but is prevented from moving laterally, substantially as described.

4. The combination, with the crane, tongs, and horizontal trunnion-shaft, of collars upon the crane engaging said shaft, said collars 25 made adjustable up and down to adjust the tongs to a higher or lower level, substantially as described.

5. In combination, the lever C, supported by a crane, the sliding jaws each engaged by 30 a pitman with a central rotary disk, and the latter connected by a connecting-rod with a hand-lever, whereby the jaws are opened or closed, substantially as described.

In testimony whereof I sign this specification in the presence of two witnesses.

DAVID O. PAIGE.
